UNITED STATES PATENT OFFICE.

ALBERT J. LINDEMANN, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

TOASTER.

Application filed October 18, 1923. Serial No. 669,242.

To all whom it may concern:

Be it known that I, ALBERT J. LINDEMANN, a citizen of the United States, and a resident of the city of Milwaukee, in the 5 county of Milwaukee, State of Wisconsin, have invented certain new and useful Improvements in Toasters, of which the following is a specification.

The improvements relate to devices for 10 toasting bread and other articles and more particularly devices of this kind in which an electric heating element is employed. They may be utilized however, for any purpose to which they are adapted.

15 Among the objects of the improvements are to provide a device of the character mentioned which will be simple and dependable and will automatically cause the reversal of the article to be toasted when the door which 20 holds it in position opposite the heating element is opened, and to obviate and overcome certain disadvantages and objections in the construction and operation thereof.

The improvements are illustrated in the 25 accompanying drawings, in which Fig. 1 is a front view of a toaster embodying the improvements with the door closed; Fig. 2 is a plan thereof; Fig. 3 is an end elevation with one door open, and Fig. 4 is a 30 vertical cross section of the same, substantially on the line 4-4 of Fig. 1, looking in the direction indicated by the arrows in that figure.

The frame of the toaster comprises a base 35 1, end uprights 2 and 3, and a perforated top 4, all secured together. Mounted in this frame is an electric heating element 5, extending from end to end thereof and supported by a platform 6, having outwardly 40 beveled surfaces at the bottom and a hanger 7 at the top. Between the end frames, at the bottom and at the front and back thereof horizontal bars 8 are supported, and on these bars the doors 9 are hinged. Other 45 bars 10 extending parallel with the bars 8 are supported slightly above and within the said bars 8, and a series of upright bars 11 forming grids or grates are secured by having their lower ends, 11^a turned around 50 the bars 8. These bars 11 extend around behind the bars 10 and up over the hanger member 7, each bar on both sides being formed of a single continuous piece of wire. Adjacent to the hinge of the door 9,

and arranged to swing between it and the bars 11, in each side, is a swinging frame 12 consisting preferably of a single piece of wire extending across the face of the grid and having its two ends 12^a turned down at each side and extending through a hole 1^a in the base. These downwardly extending end members are provided with a bend or loop 12^b which prevents them from slipping through the base and positions them thereon for pivotal movement. Their lower extremities, 12^c are turned outwardly and have supported thereon a weight bar 12^a, so that the frame 12 is constantly impelled by gravity to its foremost or outermost position by this weight.

It will be apparent from the foregoing description, that when a piece of toast or the like is placed on the door, and the door is turned upwardly to closed position the frame 12 will be pressed backwardly to the position shown on the left in Fig. 4, and that when the door is opened the bottom of the piece of toast will be thrown outwardly so that it will slide to an approximately horizontal position on the door, as shown in Fig. 3, with the face which has been exposed to the heating element down. When, therefore, the door is again closed, the opposite or untoasted side will be presented to the heating element. In this manner the article to be toasted is turned so that first one side and then the other is presented for toasting, without any turning or reversing action on the part of the door, and positively. It will also be observed that as the 90 top bar is normally in contact with the toast near the bottom of the latter when it is in toasting position, and the toast is held between it and the door, when the bar is opened the toast will be moved outwardly, across its entire width, and will not be caused to move laterally or swing sidewise over the face of the door. This is particularly advantageous when two or more pieces are being toasted on the one side—as is 100 frequently the case—and insures that they will not fall to positions where they will overlap each other and will not have to be restored to proper position by hand. It will further be seen that the device is of such 105 simple and dependable construction that there is no danger that it will get out of adjustment, even when carelessly used.

The improvements enable the maker to employ an ordinary door with a simple hinge connecting it with the toaster, and no special parts connected therewith, and to make and 5 install the turning or reversing frame before or after the door is placed in position. In fact this reversing frame may be applied to ordinary toasters which have no provision for reversal, without modification of 10 their construction, since it is entirely independent in its construction and operation of the other parts.

The lower laterally turned portions 11^b of the bars 11 form a permanent shelf on 15 which the article rests while being toasted, and this portion also has a downward inclination toward the hinge of the door. The supporting shelf may be formed of a plate or in any other manner, as may also the 20 tripping or "knock-out" frame 12 and other details of construction may be varied without departing from the spirit of the invention. The shelf may also be made horizontal, if desired, since in this form the 25 lower edge of the toast is moved off the shelf by the oscillating frame 12, and not by its own gravity.

What I claim is:

1. In combination with a toaster having 30 a frame, an upright heating element and a door mounted to open outwardly and downwardly, a turning device comprising a member extending over the face of the heating element near the bottom thereof and means 35 for constantly impelling the said member outwardly away from said heating element.
2. In combination with the parts specified

in claim 1 a weight acting as said impelling means.

3. In the combination of claim 1 the said 40 turning means being pivoted to the frame and movable to and from the heating element.

4. The combination with a frame, an upright heating element and an outwardly and 45 downwardly openable door of a turning device comprising a member mounted independently of the heating element and the door to swing outwardly near the bottom of 50 the element and toward the door, and a support for the lower edge of the article to be toasted between the door and the heating element and below the upper part of the turning device.

5. A turning device adapted to be mounted 55 between the heating element and the door of a toaster or the like, comprising a member mounted to swing between said heating element and door and means independent 60 of the door for its operation for causing it to swing outwardly.

6. In a toaster having a frame, an upright heating element and a door mounted to open outwardly and downwardly, a turning device comprising a member mounted between 65 the door and the heating device to have movement independent of the door and means also acting independently of the door for constantly pressing the said turning device in an outward direction.

Witness my hand this 13th day of October, 1923, at the city of Milwaukee, in the county of Milwaukee, State of Wisconsin.

ALBERT J. LINDEMANN.
